Primary Examiner — Elizabeth Albert(74) *Attorney, Agent, or Firm* — McHale & Slavin, PA(57) **CLAIM**

The ornamental design for a planter, as shown and described.

DESCRIPTION

FIG. 1 is a top perspective view of the planter of the present invention;

FIG. 2 is a bottom perspective view thereof;

FIG. 3 is a front view thereof, the rear view being a mirror image thereof;

FIG. 4 is a right side view thereof, the left side view being a mirror image thereof;

FIG. 5 is a top view thereof; and,

FIG. 6 is a bottom view thereof.

The portions of the planter illustrated in broken lines are included to show portions that form no part of the claimed design.
